UNITED STATES PATENT OFFICE.

WILLIAM A. WILSON, OF SANTA CLARA, CALIFORNIA.

LIQUID-FUEL BURNER.

1,232,878.

Specification of Letters Patent. Patented July 10, 1917.

Application filed January 29, 1917. Serial No. 145,084.

To all whom it may concern:

Be it known that I, WILLIAM A. WILSON, a citizen of the United States, residing at Santa Clara, in the county of Santa Clara 5 and State of California, have invented certain new and useful Improvements in Liquid-Fuel Burners, of which the following is a specification.

My invention relates to the class of liquid 10 fuel burners, and more particularly to a burner adapted to be inserted into the fire-box of a wood or coal burning cook-stove of the common type.

The object of the invention is to provide 15 a device of the type described which is cheap to manufacture; safe, simple and economical to operate; and easy to repair; and which may be installed in the fire-box of any ordinary cook-stove, to enable liquid fuel, such 20 for example as kerosene, to be used in place of wood, or coal. This will be more fully set forth hereinafter, with reference to the accompanying sheets of drawings, wherein:

25 Figure 1 is an elevation of my complete burner, showing the fuel supply tank and the connection therewith.

Fig. 2 is a plan view, enlarged, of my burner on the line 2—2 of Fig. 3, the generator pipe being omitted.

Fig. 3 is a part-sectional side elevation, taken on the line 3—3 of Fig. 2, and viewed in the direction of the arrows, the generator pipe being included.

35 Fig. 4 is a transverse section, taken in the direction of the arrows on the line 4—4 of Fig. 3.

Fig. 5 is an end elevation taken in the direction of the arrows from the line 5—5 40 of Fig. 3.

Referring more particularly to the drawings, the reference numeral 1 designates a base, preferably formed of a relatively thin strip of metal bent into rectangular shape 45 and set on edge, and adapted to lie within the fire-box of an ordinary cook-stove, not shown in the drawings, and to rest upon the usual grate thereof. Set in the upper portion of this base, and retained therein in any suitable manner, as for example by means of bolts 2, Figs. 3 and 4, is a rectangular burner casting or top plate 3, having

mixing chambers or domes 4 projecting upwardly near each end thereof, and formed as shown in Figs. 2, 3 and 4, the openings 55 4' in the tops of said burners being U-shaped, with the open side toward the front.

A burner pipe 5 extends longitudinally and centrally above the casting 3, passing freely and revolubly through apertures 6 in 60 the walls of the mixing chambers or domes 4. Said pipe is provided with an orifice or gas exit 7, in its upper side, disposed centrally of each burner opening 4', through which the vaporized fuel is emitted. One 65 end of the burner pipe 5 is capped, as at 8, and the other carries an upturned elbow 9, the shoulders 8' and 9' formed by said cap and elbow serving to limit the lineal movement of said pipe 5 to that necessary to 70 allow for expansion and contraction. The fuel jet or gas-exit orifices 7 are thus positively and accurately located with respect to the mixing chambers or domes 4.

Lying parallel with and above the burner 75 pipe 5 is a vaporizer or generator pipe 10, connected at one end with said burner pipe by means of an elbow 11, a short pipe or nipple 12, and the elbow 9. The other end of said generator is connected, by a feed 80 pipe 13, with the fuel tank 14, Fig. 1. A portion of the feed pipe 13, shown at 13' in Fig. 1, lies in lineal alinement with the burner pipe 5, and a suitable packed slip joint 15, of any well known type, is inserted 85 in said feed pipe portion 13', so that the entire assemblage of generator and burner pipes may be rocked about the burner pipe as an axis for a purpose to be presently described. A bracket 16 is secured to one end 90 of the base 1, and at its upper portion has an arcuate surface 17, Fig. 5, upon which the feed end of the generator 10 may rest, and said arcuate surface is bounded by lugs 18, which form spaced seats and limit the 95 lateral rocking movement of said generator.

The supply of fuel is preferably controlled by a safety shut-off valve 19 in the feed pipe 13 near the fuel tank 14, a regulating needle valve 20, near the generator, and a valve 21 100 in the burner pipe 5 between the two burners, which may be used to shut off or regulate one burner independently of the other.

The generator 10 comprises an outer pipe,

within which is carried a bundle or group of closely parallel tubes 22—Figs. 3 and 5, preferably of copper, and of relatively small diameter. The function of these tubes is to 5 provide as great a surface as possible for contact with the fuel, in order to conduct as much heat as possible from the outer pipe 10 to the fuel, to insure complete vaporization thereof, without unduly obstructing the 10 flow of said fuel. It is understood, of course, that the fuel flows both through and around the tubes 22, said tubes acting solely as heat conducting and radiating surfaces.

The generator pipe 10 serves as a support 15 for flame spreaders or deflectors 23, Figs. 1, 3 and 4, one positioned over each mixing chamber 4. These flame spreaders each comprise a circular plate 23, preferably formed with an annular downwardly turned 20 rim 23', and having a lug or stem 24 formed upon the upper side. Said lug 24 is bored, as at 25, Fig. 4, and through said bore is freely passed the generator pipe 10. Any suitable means, not shown, may be employed 25 for retaining the flame spreaders in lateral position upon the generator pipe.

The burner casting 3 is formed with a lineally disposed trough 26 extending the entire length of said casting in front of the 30 mixing chambers 4, and with a ridge or web 27 extending between the rear portions of said mixing chambers, and rising from the surface of the casting 3. In starting the burner, liquid fuel is poured into the initial 35 firing trough 26. Said liquid fuel in said trough is then ignited, and the burner and generator pipes are rocked to bring the latter into its forward position, in which position it is heated by the burning fuel in the 40 trough 26, until sufficiently hot to vaporize the fuel within it. The control valve 20 is then opened, and the fuel, passing through the generator 10, is vaporized, and issues from the orifices 7 as a gas. Said gas is 45 mixed, in the mixing chambers 4, with air drawn upward through said mixing chambers and the base 1, and burns, at said burners, with a blue flame. The generator and burner pipes may then be rocked to their 50 vertical position, or if it be desired to direct the flames toward the front of the fire-box, they may be left in their forward position.

It will readily be seen that, on account of the built-up construction of the device, the 55 various parts thereof may be easily and quickly removed for repair or replacement. Thus the generator 10 may be readily removed, for cleaning or replacement, without removing the burner pipe 5; and similarly, the burner casting 3 may be replaced, 60 without necessitating renewal of the base 1. The flame spreaders 23, moreover, being firmly carried by the generator 10, are not apt to become loose or displaced, yet they

may be quickly renewed, upon the removal 65 of said generator pipe.

I claim:—

1. A liquid fuel burner comprising a suitable base, a top plate carried thereby and having a mixing chamber near each end, a longitudinal firing trough disposed along one side of the top plate, a burner pipe extending through the walls of the mixing chambers and having a gas exit opening into each mixing chamber, said burner pipe being capable of only a limited lateral movement and revolubly mounted at its ends in the walls of the mixing chambers, a controlling valve in the burner pipe to permit the use of one burner independently of the other, an overlying parallel generator pipe connected with the burner pipe, a series of openended parallel tubes disposed within the generator pipe and extending the full length thereof, a supply pipe connected with the generator pipe for feeding fuel thereto, and a vertical bracket secured to one end of the base and formed in its top with a pair of spaced seats engaging the generator pipe for maintaining the same in 90 different positions, substantially as described.

2. A liquid fuel burner comprising a base, a top plate on said base having an initial firing trough therein, said plate having near each end upstanding wall portions forming openended mixing chambers of substantially U-shaped formation, the vertical wall on one side of each chamber being removed, a burner pipe extending through said chamber walls and having a gas exit discharging into each chamber and capable of an oscillating movement, an overlying generator pipe extending parallel with the burner pipe and exposed to the flame regions of the burners, a pipe with elbow connections at each end detachably joining one end of the generator pipe with the adjacent end of the burner pipe and limiting the longitudinal movement of said pipes, a valve in the burner pipe intermediate the gas exits, a vertical bracket secured to one end of the base and formed at its top to support the generator pipe when moved from one position to another, a source of liquid fuel supply and a controllable connection between said supply, and the generator pipe.

3. A liquid fuel burner comprising a base, a top plate carried thereby and having a mixing chamber near each end, a firing trough disposed on one side of the top plate, a burner pipe having a gas exit opening in each mixing chamber and revolubly mounted at its ends, a controlling valve in the burner pipe to permit the use of one burner independently of the other, an overlying parallel generator pipe connected with the burner pipe, a series of open-ended parallel tubes

disposed within the generator pipe and extending the length thereof, a supply pipe connected with the generator pipe for feeding fuel thereto, and means for maintaining the generator pipe in its different positions, substantially as described.

5 In testimony whereof I have signed my

name to this specification in the presence of two subscribing witnesses.

WILLIAM A. WILSON.
